UNITED STATES PATENT OFFICE.

SOLOMON W. BATES, OF PORTLAND, MAINE.

MACHINE FOR MAKING MATCH-CARDS.

SPECIFICATION forming part of Letters Patent No. 605,593, dated June 14, 1898.

Application filed January 24, 1898. Serial No. 667,710. (No model.)

To all whom it may concern:

Be it known that I, SOLOMON W. BATES, a citizen of the United States of America, and a resident of Portland, county of Cumberland, 5 State of Maine, have invented certain new and useful Improvements in Machines for Making Match-Cards, of which the following is a specification.

My invention relates to a machine for cutting cards of pointed matches from veneer strips; and it is particularly designed as an improvement on the machine shown in Letters Patent No. 560,939, dated May 26, 1896, to C. F. Scamman.

15 In the Scamman machine above spoken of there was a stationary splitting-knife below the bed of the machine and a cutting-block above, which reciprocated against the upturned edge of the splitting-knife, the veneer strip being fed forward between the splitting-knife and the cutting-block by means of suitable feed-rolls. The points of the splints were formed by means of a V-shaped end to the splitting-knife, which cut out a triangular notch between the adjacent matches at 20 the same time they were split. The splitting-knives extended only part of the way across the veneer strip, so that the matches were held together by a solid or uncut section in 25 the middle of the veneer. The defect of the Scamman machine, so far as I can judge from my own experience, was that as the V-shaped notching or pointing knife passed through the veneer in line with the splitting-knife it had 30 a tendency to spread the ends of the adjacent matches, forming a point which was thicker on one side than the other. In order to remedy this defect, I place the V-shaped notching-knife one or more spaces ahead of the 35 splitting-knife, so that it cuts through the solid edge of the veneer strip instead of cutting the end of the match while the latter is being split off by the splitting-knife. The tendency of the notch to spread is thus overcome and a square point is formed.

40 Another advantage of my construction is that the point of the V, being no longer connected with the straight splitting-knife, is more easily kept sharp than when the knife 45 was made on the old plan.

I have found that the clogging of the V-shaped knife by the triangular pieces which

are forced into it has a tendency to cause the notch to spread, and to remedy this defect I make use of an ejector for throwing out the 55 pieces at each reciprocation of the machine, so that the notching-knife always has a free cut.

I illustrate my invention by means of the accompanying drawings, in which—

Figure 1 represents a section of the essential parts of the Scamman machine so far as they are necessary to explain my present invention. Fig. 2 is a perspective view of the knives, showing the cutting-block in its relative position; and Fig. 3 is a diagram showing 65 the manner in which the veneer strip is cut.

B is the bed of the machine; C C, the feed-rolls; F, the splitting-knife; E, the cutting-block, and d is the lifting-plate of the machine. These parts are old and well known 70 and need no detailed description.

The notching-knives H are made V-shaped and are secured, as herein shown, to the ends of the splitting-knife one space ahead of the latter, so that they will cut out the notches 75 from the solid edge of the veneer before the latter comes to the splitting-knife, as clearly shown in Fig. 3. The two ends of the splitting-knife are divided by a notch or space f, which leaves an uncut portion in the center. 80

G represents the veneer strip, and h is the triangular piece which is cut out by the knife H.

For the purpose of throwing out the triangular piece h at each cut of the knife I secure an ejector i to the end of the reciprocating cutting-block E, the lower end being bent at right angles and extending into the space 85 formed by the sides of the V-shaped knife H.

It is evident that the notching-knife H 90 may be placed more than one space ahead of the splitting-knife, and it may be secured in the machine without being fastened to the knife F. The V-shaped notching-knife cutting, as it does, into the solid edge of the 95 veneer strip at each cut of the machine and being kept clear from the triangular pieces, which tend to jam in and fill it up, cuts a clean notch having the same width on one side as on the other, and the result is that the 100 matches all have perfect ends.

I claim—

1. In a machine for cutting cards of pointed matches from veneer strips, the combina-

tion of a cutting-block and a splitting-knife adapted to reciprocate, one with relation to the other, means for feeding the veneer strip between them and a V-shaped notching-knife set one or more spaces ahead of said splitting-knife and having the open end of the V turned outward, whereby the notches are cut with a single stroke of said knife.

2. In a machine for cutting cards of pointed matches from veneer strips, the combination of a cutting-block and a splitting-knife adapted to reciprocate, one with relation to the other, means for feeding the veneer strip

between them, a V-shaped notching-knife set one or more spaces ahead of said splitting-knife and having the open end of the V turned outward and an ejector for knocking out from said V-shaped knife the triangular pieces cut by said knife at each reciprocation of the machine.

Signed by me, at Portland, this 22d day of January, 1898.

SOLOMON W. BATES.
